(57) **CLAIM**

The ornamental design for a helmet-mounted light, as shown and described.

DESCRIPTION

FIG. 1 is a front elevational view of the helmet-mounted light;
FIG. 2 is a top plan view thereof;
FIG. 3 is a right-side elevational view thereof;
FIG. 4 is a left-side elevational view thereof;
FIG. 5 is a rear elevational view thereof;
FIG. 6 is a bottom plan view thereof;
FIG. 7 is a front, bottom perspective view thereof; and,
FIG. 8 is a reference view showing the helmet-mounted light attached to a helmet.
The broken lines depict environmental subject matter only and form no part of the claimed design.
